DESIGN FOR A SHUFFLEBOARD CUE HEAD

Carl E. Gunklach, Oakwood, Ohio

Application July 25, 1946, Serial No. 131,928

Term of patent 7 years

(Cl. D34—5)

To all whom it may concern:

Be it known that I, Carl E. Gunklach, a citizen of the United States, residing at Oakwood, in the county of Montgomery and State of Ohio, have invented a new, original, and ornamental Design for Shuffleboard Cue Heads, of which the following is a specification, reference being had to the accompanying drawing, forming part thereof, in which

Fig. 1 is a perspective view of a shuffleboard cue head, showing my new design;

Fig. 2 is a top plan view of the shuffleboard cue head; and

Fig. 3 is a front view of the shuffleboard cue head.

I claim:

The ornamental design for a shuffleboard cue head, as shown.

CARL E. GUNKLACH.
